UNITED STATES PATENT OFFICE

103,172

DESIGN FOR A SHIELD FOR AN AUTOMOBILE RADIATOR

Ben Wengard, Waterloo, Iowa

Application August 21, 1936, Serial No. 64,508

Term of patent 7 years

To all whom it may concern:

Be it known that I, Ben Wengard, a citizen of the United States, residing at Waterloo, in the county of Blackhawk and State of Iowa, have invented a new, original, and ornamental Design for a Shield for an Automobile Radiator, of which the following is a specification, reference being had to the accompanying drawing, forming a part thereof.

Fig. 1 is a front elevation of a shield for an

automobile radiator, showing my new design, with the flap portion in secured elevated position, and Fig. 2 is a similar view thereof, the flap being lowered and secured in an adjusted position.

I claim:

The ornamental design for a shield for an automobile radiator, as shown and described.

BEN WENGARD.
